UNITED STATES PATENT OFFICE.

JOHN M. LUDWIG AND AMOS LEFFARGE, OF OAKLANDON, INDIANA.

MAIL-BAG-HOLDING DEVICE FOR MAIL-CRANES.

SPECIFICATION forming part of Letters Patent No. 792,714, dated June 20, 1905.

Application filed December 30, 1904. Serial No. 239,020.

To all whom it may concern:

Be it known that we, JOHN M. LUDWIG and AMOS LEFFARGE, citizens of the United States, residing at Oaklandon, in the county of Marion 5 and State of Indiana, have invented certain new and useful Improvements in Mail-Bag-Holding Devices for Mail-Cranes, of which the following is a specification.

This invention relates to improvements in cranes for holding mail-bags in convenient position to be caught by the arm extended from a rapidly-moving mail-car in accordance with the present daily practice, and has special reference to the holding or clamping device that has immediate connection with the handle-straps of the mail-bag; and the object of the invention is to provide a holding means that will hold the bag with security against wind and the suction caused by the motion of the train and all other disturbing influences except the strong and positive action of the catcher-arm of the mail-car. Under present methods the mail-bag straps are caught around fixed longitudinal hooks extended from the ends of the crane-arms, and much damage is done, particularly to the mail-bag, due to the unyielding nature of those fastenings, and their imperfect hold on the bag frequently permits the latter to be drawn therefrom and the bag and contents injured by the bag being drawn under the wheels of the train.

We accomplish the objects of the invention by the mechanism illustrated in the accompanying drawings, in which—

Figure 1 is a perspective view of the upper portion of a mail-crane, showing the arms in operative position holding a mail-bag, said arms being provided with our improved gripping devices. Fig. 2 is a detail in top view and partial horizontal section of the gripping-fingers. Fig. 3 is a top plan view of the gripping-fingers and head in which they are mounted, showing the arm to which the head is applied in dotted lines and showing the gripping-fingers in their opposite position also in dotted lines; and Fig. 4 is a detail in side view of the spring-barrel removed from the other parts of the device.

Like characters of reference indicate like

parts throughout the several views of the drawings.

5 is the vertical post of a mail-bag-holding crane, 6 an arm which is pivotally secured at the top of the post, and 7 an arm which is pivotally secured below the top arm, all of 55 said parts being of the usual and well-known construction and located in the usual way by the side of a railroad-track on which mail-trains are run and to which mail-bags are to be delivered without stopping or arresting 60 the speed of the train.

8 is the body of our gripping device, which is bolted or secured in any substantial manner to the respective ones of said arms 6 and 7 and may be applied to either the top or 65 bottom faces of said arms. In the drawings, Fig. 1, this body is shown as applied to the under face of arm 6 and to the upper face of arm 7; but this application in one or both cases may be reversed, if desired. At the 70 outer end of the body 8 is a head 9, comprising two parallel horizontal plates which are separated from each other, as shown in Fig. 1, a suitable distance to allow the end of the gripping-finger 10 to be inserted between said 75 plates. The inner or inserted end of finger 10 is secured between said plates by means of the pivot 11, whereby said finger may be moved in a horizontal plane over an arc of one hundred and eighty degrees from a position 80 on one side of the head parallel with the railroad-track to a diametrically opposite position also parallel with said track. The parallel plates of head 9 make a close fit with the inserted end of finger 10 and keep said finger 85 in constant horizontal position. The finger 10 is perforated horizontally adjacent to the head and also vertically through said horizontal perforation, and the flat end of a second finger 12 is inserted into the horizontal perforation of finger 10 and is pivotally secured there by means of a pin 13. These two fingers 10 and 12 are spread apart adjacent to their pivotal points, but are curved inwardly 90 as they approach their outer ends, so as to 95 provide points of contact when the fingers are drawn together and a sufficient opening between said contact-points and the pivotal

points of the fingers to receive therein the holding-straps 14 of mail-bag 15. The extreme ends of the two fingers are spread or oppositely curved to facilitate the insertion between them of said holding-straps. The fingers will be preferably round in cross-section, or at least rounded at the corners, so as to make the wearing friction against the straps 14 as little injurious to said straps as possible.

10. Passing through fingers 10 and 12 is a bolt 16, having one end threaded and having a head at its opposite end to provide a bearing for the bolt against its adjacent finger.

15. 17 is a cylindrical shell or barrel open at one end and closed at its opposite end, except for a central opening through said closure just large enough for the passage of bolt 16. Placed within the barrel 17 is the coil-spring 18, and this spring and barrel for operative purposes are placed in the position shown in Fig. 2, with the bolt 16 passing through the spring and through the perforated end of the barrel. The sides of the barrel at diametrical opposite portions are slotted, as clearly shown 20 in Fig. 4, to receive the finger 10 in said slot, as shown in Figs. 2 and 3. After the barrel and its spring have been assembled on bolt 16 a nut 19 is screwed upon the threaded end of the bolt against the barrel and the spring compressed until its tension draws the two fingers 10 and 12 together with the requisite force. The bolt 16 has a series of small transverse holes, and when the nut 19 is screwed up to the desired position on said bolt it is 25 there securely retained by means of a pin 2, which is driven into the nearest hole 20.

In the drawings, Fig. 1, the body 8 is shown as being formed out of two plates which are the continuation of the two plates which go 30 to make up the head 9; but in practice, if it is so desired, the body may be made solid, as would probably be the case where the same was of cast metal.

In its practical use the arms 6 and 7 of the 35 crane will be drawn together and the holding-straps 14 of the mail-bag inserted between each pair of the holding-fingers, as above described. The operator will see to it that the fingers are turned parallel with the railway-track and pointing in the direction toward which the mail-train is moving. When the 40 catcher-arm from the mail-car contacts with the mail-bag, the holding-straps of the latter will be drawn out from between the elastic-ally-yielding fingers. It is understood, of course, that the mail-bag is of the usual construction, using either leather straps or metal holding-rings, as the case may be.

Having thus fully described our invention, 45 what we claim as new, and wish to secure by Letters Patent of the United States, is—

1. A bag-holding device for mail-cranes comprising a pair of horizontally-adjustable fingers, said fingers being pivoted together

and adjustable to or from each other in a horizontal plane, and elastic means for holding them normally in contact.

2. The combination with the arms of a mail-crane of a body fastened to said arms, said body having a head extending past the end of its arm, said head comprising a pair of horizontal separated plates, a finger pivotally mounted between said plates, a second finger pivotally secured to the first finger adjacent to said head, said fingers being bent for the purposes described, a bolt passing through both of said fingers, said bolt having a head at one end and having its other end screw-threaded, a nut on said bolt, and a spring between said nut and the adjacent finger.

3. A bag-holding device for mail-cranes comprising a head with two horizontal parallel separated plates, a finger pivotally mounted between said plates, a second finger pivoted to the first finger, said fingers being bent as shown, a bolt passing through both fingers having a threaded end, and a head at its opposite end, a nut screwing on the threaded end of the bolt, and a spring between the nut and its adjacent finger.

4. In a holding device for holding mail-bags on mail-cranes, a head comprising two horizontal separated plates, a finger pivoted between said plates, a second finger pivoted to the first finger, both of said fingers being bent as shown and rounded in cross-section at their outer ends, a bolt passing through both fingers having a threaded end, and a head at its opposite end, a nut on the threaded end of the bolt, a cylindrical barrel between the nut and its adjacent finger and surrounding the bolt, said barrel having side slots to receive the finger, and a spring in said barrel surrounding the bolt and between the outer end of the barrel and the adjacent finger.

5. In a mail-bag holder for mail-cranes, a head in two horizontal separated plates, a finger pivoted between said plates, a second finger pivoted to the first finger, both fingers being bent as shown, a bolt passing through both fingers, said bolt having a threaded end and a head at its opposite end, a nut on the threaded end of the bolt, a barrel between the nut and the adjacent finger, surrounding the bolt, a spiral spring surrounding the bolt and located in the barrel, between the outer end of the barrel and the adjacent finger, said bolt having a series of transverse perforations, and locking-pins driven into said perforations.

In witness whereof we have hereunto set our hands and seals, at Indianapolis, Indiana, this 19th day of December, A. D. 1904.
